UNITED STATES PATENT OFFICE.

BENJAMIN F. BAILEY, JR., OF LUCEDALE, MISSISSIPPI, ASSIGNOR OF ONE-THIRD TO
BENJAMIN I. TROTTER, OF LUCEDALE, MISSISSIPPI.

LIGHT DIMMER FOR MOTOR VEHICLES.

Application filed January 20, 1922. Serial No. 530,597.

To all whom it may concern:

Be it known that I, BENJAMIN F. BAILEY, Jr., a citizen of the United States of America, and a resident of Lucedale, county of George, and State of Mississippi, have invented certain new and useful Improvements in Light Dimmers for Motor Vehicles, of which the following is a full and clear specification.

10 The object of this invention is to provide a simple device whereby the dimmer resistance may be shunted into the circuit to dim the lights by means of one of the control devices usually mounted on the steering-head, the finger-lever of this control device being arranged as usual in a position for greatest convenience in manipulating. In this way, I provide a means for opening and closing the dimmer-switch without adding 15 to the vehicle any additional manually-operable devices on the steering-head or on the instrument-board, and at the same time I provide for operating the dimmer in such a convenient way that the driver will be induced to dim his lights whenever it is desirable to do so.

In the drawing—

Fig. 1 is a diagrammatic view of one system in which my invention may be conveniently embodied;

Figs. 2 and 3 are detail views hereinafter described.

In the drawing, I show my dimmer appliance inserted in the circuit at a point between the selective-switch 5 and the usual bright-light terminal 6 on the usual terminal-block 7. The battery or generator, or both, is illustrated conventionally at 8, and the usual bright-light conductors 9 extend from the terminal 6 to the head-lamps.

In the form of device I have chosen for illustrating my invention, I use a block of insulating material 10 and fastened to 45 the opposite edges thereof are metallic terminal-plates 11. One of these plates 11 is folded over on top of the block 10 and made resilient to form a resilient contact point 12. The other plate 11 is extended 50 upwardly and folded upon itself to form a curved contact-finger 13 having a contact point 14 which normally contacts with point 12 but which may be separated from the point 12 by springing the finger 13 outwardly, as shown in Fig. 2. One of the

plates 11 is connected by a conductor 15 to the head-lamp-terminal 6 and the other is connected by a conductor 16 to the conductor 17 leading from the selective-switch, this connection being desirably secured by a 60 screw 18 screwed into a convenient part of the dash-board on the inner face thereof.

The insulating-block 10 contains a transverse resistance element 19 which connects the two plates 11 at a point between the contacts 12—14 and the point of connection of the two conductors 15—16. I screw the block 10 on the inner face of the dash-board in such relation to the usual spark-control-rod 20 that an arm 21 fastened to said rod 70 will, when the spark-control-rod is rotated to retard or advance the spark, strike the upper curved end of the finger 13 and separate the contacts 12—14. This arm 21 is provided with a fiber wheel 22 which makes 75 the contact against the finger 13 and at its other end it is formed into a U-shaped clip 22' which may be clamped on the control-rod 20 in any position desired by means of a set-screw 23.

In installing the device, it has been found desirable to so position the contact-breaker-arm 21 on the spark-control-rod that it will lie close to the finger 13 when the spark-lever is adjusted to average running position, so that a slight movement of the finger-lever in the direction to retard the spark will open the contacts 12—14 and thus throw in the resistance element 19 and dim the lights. I have found that this device 90 may be thus applied to the spark-control-rod without materially interfering with the operation of the spark-control, since the slight movement from average driving position that is required to throw in the resistance element will not be sufficient to noticeably disturb the spark adjustment.

With this arrangement, it will be seen that the greatest degree of convenience possible is obtained in the matter of putting 100 the dimmer resistance in the circuit, since this operation is performed through the medium of the usual finger-lever on the steering-head. This not only contributes to convenience in operation, but avoids the providing of an additional manual switch on 105 the dash-board. The making of the operation an extremely convenient one is particularly the feature of my invention because in this way the driver will be strongly induced 110

- to throw in the dimmer whenever it is at all necessary, whereas with the dimmer capable of being put into operation only by the manipulation of a separate manual switch mounted somewhere on the instrument-board, the driver would inconvenience himself to put the dimmer in only in special cases, if at all. In my device, the putting of the dimmer in is such a trivial matter that there will be no inducement to side-step this responsibility, and consequently the driver will soon acquire the habit of dimming his lights on every occasion where it may possibly be needed.
- I have shown my device as adapted to a Ford car, but it will be understood that details of construction may be modified to render it applicable to other makes of cars and even to electrically-driven cars.
- I do not desire to be understood as limiting myself to the precise details of construction and arrangement shown, as variations and modifications therefrom may be made without departing from the spirit and scope of my invention and improvements. I therefore reserve the right to all such variations and modifications as properly fall within the scope of my invention and improvements and the terms of the following claims.
- What I claim is:
1. A motor vehicle having a spark-control rod and a finger-piece on the steering-head for manipulating it, a lighting system for the headlights of the vehicle, a dimmer-switch in the supply circuit thereof, and means whereby this switch may be opened and closed by a rotative operation of said spark-control rod without interfering with the regular use of said spark-control rod or restricting its range of movement.
  2. A motor vehicle having a spark-control rod and a finger-piece on the steering-head

for manipulating it, a lighting system for the headlights of the vehicle, a dimmer-switch in the supply circuit thereof, and means whereby this switch may be opened and closed by operation of said spark-control rod, said means embodying an arm adjustably attached to the control-rod and a resistance switch mounted on an adjacent support in position to be opened through the medium of said arm upon rotation of the control-rod.

3. A motor vehicle having a spark-control rod and a finger-piece on the steering-head for manipulating it, a lighting system for the headlights of the vehicle, a dimmer-switch in the supply circuit thereof, and means whereby this switch may be opened and closed by operation of said spark-control rod, said means consisting of an operating arm fastened to the spark-control rod, a block of insulation adjacent the dash-board and carrying normally-closed contacts, one of which carries a finger adapted to be operated by said arm, a resistance element in the block, and conductors leading from the respective contacts to the lamp-supply conductors and to the current source.

4. A motor vehicle having a spark-control rod and a finger-piece on the steering-head for manipulating it, a lighting system for the headlights of the vehicle, a dimmer-switch in the supply circuit thereof, and an element attached to the rod at such a point that it will operate the switch by a rotative operation of the spark-control rod at an intermediate point in the range of movement thereof, whereby the regular use of the spark-control rod will not be in any wise interfered with.

In testimony whereof I hereunto affix my signature.

BENJAMIN F. BAILEY, JR.
